PILE HAMMER

Ole Peterson, Houston, Tex.

Application March 1, 1934, Serial No. 713,511

6 Claims. (Cl. 61—73)

This invention relates to a pile hammer.

An object of the invention is to provide an implement for driving piles particularly sheet piling.

5 Another object of the invention is to provide novel means for guiding the drive ram forming a part of the hammer.

A further object of the invention is to provide a pile hammer having means for cushioning the 10 stroke of the ram to prevent the upper end of the piling from becoming distorted during the driving operation.

With the above and other objects in view, the 15 invention has particular relation to certain novel features of construction, operation and arrangement of parts, an example of which is given in this specification and illustrated in the accompanying drawing, wherein:

Figure 1 shows a side view of the hammer as 20 applied to sheet metal piling.

Figure 2 shows an edge view thereof partly broken away.

Figure 3 shows a cross sectional view taken on the line 3—3 of Figure 1, and

25 Figure 4 shows an enlarged cross sectional view, taken on the line 4—4 of Figure 2.

In the drawing the numeral 1 designates the pile bonnet whose upper end is provided with a deep socket 2 and whose lower end is reduced 30 and formed into prongs 2', 2' having the upwardly converging slot 3 between them to receive the upper end of the web of the piling 4 to be driven.

The bonnet 1 has the oppositely arranged vertical grooves 5, 5 to receive the spaced leads or 35 guides 6, 6. Between the upper ends of these guides is the drive ram 7 which may be mortised into said ends of the guides as shown and the upper ends of the guides and the drive ram are securely bolted together. The lower end of the 40 ram is reduced and slightly tapered, forming the drive point 8 which is aligned above the recess 2. In the bottom of this recess there is a resilient shock absorbing element 9 preferably formed of wood or similar material to receive the impact 45 of the drive point 8 and to absorb the shock and thereby protect the upper end of the piling from distortion. The lower ends of the guides 6 have the diverging faces 9', 9', to easily direct the guides over the piling and above said faces 9', the 50 guides are inwardly thickened forming the bearings 10, 10 which closely engage the piling on opposite sides.

When the bonnet 1 is located in proper position on the upper end of the piling to be driven the 55 ram and guides 6, 6 may be alternately elevated

and dropped and the piling thus driven by the successive impacts of the drive ram against the bonnet. For the purpose of operating the hammer a cable 11 is provided whose lower end is attached to a link 12 which is fitted into a socket 13 in the upper end of the ram 7 and a bolt 14 is fitted through the ram and through said link. The cable 11 operates over a pulley 15, carried by the boom as 16 and any suitable mechanism may be used for alternately pulling and releasing the cable 11 to elevate and drop the ram. The piling 4 serves as a track for the guides 6 and the invention dispenses with the necessity of the erection of separate guides or leads for the ram now commonly used in pile hammer 15 equipment.

The drawing and description disclose what is now considered a preferred form of the invention by way of illustration only, while the broad principle of the invention will be defined by the appended claims.

What I claim is:

1. A pile hammer comprising a bonnet shaped to receive the upper end of piling, a drive ram, guides embracing and having a slidable connection with the bonnet and to which the ram is fixed.

2. A pile hammer comprising a bonnet shaped to receive the upper end of piling, a drive ram, guides having a slidable connection with the bonnet and to which the ram is fixed, said guides having bearings arranged to ride against opposite sides of the piling being driven.

3. A pile hammer comprising a bonnet adapted to rest on the upper end of a pile to be driven, a ram arranged to be elevated and dropped, means guided by the pile and arranged to guide the ram, when dropped, onto the bonnet, said ram and bonnet being provided one with a recess having a cushioning element therein and the other with a drive point aligned with said element.

4. In combination, an anvil block adapted to be supported on a pile to be driven, a driving ram above said block and mounted to be elevated and dropped, means carried by the ram and embracing the block and shaped to be guided by the pile and effective to guide the ram, when dropped, onto the anvil block.

5. In combination, an anvil block adapted to be supported on a pile to be driven, a driving ram above said block and mounted to be elevated and dropped, means carried by the ram and shaped to be guided by the pile and effective to guide the ram, when dropped, onto the anvil block,

said block having a recess and a resilient cushion in the recess, and a drive point on the ram arranged to strike the cushion, when the ram is dropped, to cushion the impact.

5 6. In combination, a block adapted to be supported on a pile to be driven, a driving ram above the block and mounted to be elevated and dropped, spaced guides carried by the ram and embracing the block and shaped to be guided by

the pile and effective to guide the ram when dropped on to said block, said ram and block being provided, one with a recess having a resilient cushion therein, and the other having a drive point aligned with the cushion whereby the impact of the ram, when the latter is dropped, will be cushioned. 5

OLE PETERSON.
